Primary Examiner — Sanjeev Paul*Assistant Examiner* — Breana Copeland(74) *Attorney, Agent, or Firm* — Ipusa, PLLC(57) **CLAIM**

The ornamental design for a digital camera, as shown and described.

DESCRIPTION

FIG. 1 is a perspective view of a digital camera, showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The broken lines shown in the drawings are for the purpose of illustrating portions of the digital camera that form no part of the claimed design.

1 Claim, 4 Drawing Sheets(56)
